(57) **CLAIM**

The ornamental design for a light bar, as shown and described.

DESCRIPTION

FIG. 1 is a perspective view of a first embodiment of the light bar;

FIG. 2 is a front view thereof;

FIG. 3 is a back view thereof;

FIG. 4 is a top view thereof;

FIG. 5 is a bottom view thereof;

FIG. 6 is a right view thereof;

FIG. 7 is a left view thereof;

FIG. 8 is a perspective view of a second embodiment of the light bar;

FIG. 9 is a front view thereof;

FIG. 10 is a back view thereof;

FIG. 11 is a top view thereof;

FIG. 12 is a bottom view thereof;

FIG. 13 is a right view thereof;

FIG. 14 is a left view thereof;

FIG. 15 is a perspective view of a third embodiment of the light bar;

FIG. 16 is a front view thereof;

FIG. 17 is a back view thereof;

FIG. 18 is a top view thereof;

FIG. 19 is a bottom view thereof;

FIG. 20 is a right view thereof;

FIG. 21 is a left view thereof;

FIG. 22 is a perspective view of the fourth embodiment of the light bar;

FIG. 23 is a front view thereof;

FIG. 24 is a back view thereof;

FIG. 25 is a top view thereof;

FIG. 26 is a bottom view thereof;

FIG. 27 is a right view thereof; and,

FIG. 28 is a left view thereof.

The dashed broken lines in the figures show portions of the light bar that form no part of the claimed design.

(Continued)

The dot and dash line-shading depict, inter alia, character and/or contour of the surfaces of the light bar; the line-shading is not a graphical symbol indicating material or function of a feature.

1 Claim, 28 Drawing Sheets
